NOOSE RELEASING HONDA

Edward A. Hoody, Dundalk, Md.

Application June 2, 1950, Serial No. 165,765

2 Claims. (Cl. 24—129)

1

The present invention relates to certain new and useful improvements in toys and playthings and has more particular reference to a lariat which is safe and suitable for use by youngsters when playing the game of cowboys.

It is a matter of common knowledge to those familiar with toy-type lassos and lariats that they can actually become dangerous instrumentalities especially in the hands of larger boys taking advantage of smaller ones, once the running loop or noose is around the body or other part of the captured youngster. There has long been a demand for a toy lasso with a releasable safety-type running noose. It is therefore the object of the instant invention to attempt to solve the problem of safe play with lassos by the adoption and use of a pressure responsive self-opening and detachable noose.

More specifically, the invention has to do with a honda in the form of a block of suitable shape, size and material, preferably commercial plastics, which functions as a noose forming, adjusting and releasing device. To this end the block has means for anchoring one end of the noose and complementary means whereby an adjacent portion of the rope may be bent and formed into a running noose, the latter means including a restricted side slot through which the coacting portion of the rope may be extracted when the tightening pressure of the noose about the body of the victim develops a predetermined unsafe bonding and strangling pressure.

Other objects and advantages will become more readily apparent from the following description and the accompanying illustrative drawings.

In the accompanying sheet of drawings wherein like numerals are employed to designate like parts throughout the views:

Figure 1 is a perspective view of the noose forming, holding and releasing honda constituting the novel subject matter of the instant invention;

Figure 2 is a view with parts in section and elevation of the honda per se;

Figure 3 is a perspective view of the same;

Figure 4 is an end elevation looking from right to left and based on the showing made in Figure 3; and,

Figure 5 is likewise an end elevation looking at the curvate end of the block-type honda shown in Figure 2.

The lasso comprises a suitable length of rope or the like one end of which is denoted by the numeral 6 and the other end by the numeral 8, the latter end being provided with an anchoring knot 10. The noose portion is denoted by the

numeral 12 and the novel noose forming, retaining and releasing honda or device is denoted by the numeral 14. This device, as before indicated, takes the form of a block which may be said to be substantially sector-shaped in top plan shown, for example, in Figure 2. One edge portion 15 is substantially straight at one end and the opposed edge portion is inclined as at 16 and the two edges 15 and 16 converge to form a relatively narrow straight across end portion 17. The opposite end portion is somewhat wider and of the approximate curvature shown at 18. The straight edged side is formed with an open ended rope accommodating channel 20. The channel is provided along one side with a restricted rope releasing slot 22. The width of this slot in practice may perhaps be approximately $\frac{1}{3}$ that of the diameter of the channel 20. The channel is of a cross section slightly greater than the rope which fits into it, giving the rope free sliding play. If desired, certain surfaces may be rounded as at 24 to facilitate withdrawing of the rope and to minimize undue chafing of the rope. The numeral 26 designates an open ended curvate bore having one end 28 opening through the curvate edge of the block and the other end 30 opening through the straight diverging edge portion 16 of the block.

In making a noose and thus producing a complete lasso the user, before the knot 10 is formed, will pass the end portion 8 of the rope from left to right through the channel 20 in Figure 1 for example. When the free tip portion of the rope emerges through the right hand end of the channel 20 the user will catch hold of it and pull the rope on through and will then insert said end of the rope into the passage or bore 26 by way of the forward or outer end portion 28 and he will continue to force the rope through bit by bit until the tip end emerges through the rear opening 30. He will then tie the half-hitch knot 10. Now, by simply pulling on the rope between the two passages, that is the channel on the one side and the bore 26 on the other side the user may produce a noose, namely, a running type noose of the desired size. The purpose of the bore being in the form of an arc is to keep the rope portions separated and to form a successful loop.

It is obvious that the article herein shown and described is a piece of merchandise wherein a "cowboy" may rig up his own lasso and use it with complete safety to all concerned. He cannot encircle the noose around a playmate and keep him tied up "for keeps." This is true because the safety opening noose will permit the

rope to be ejected by way of the slot 22 when sufficient pressure is exerted on the end portion 26. That is to say, when the pull on the rope end 26 becomes sufficiently taut that the noose would begin to unduly curb and bind the captive, the releasable end portion of the rope will automatically pull out through the slot 22 and the captive will be freed in an obviously harmless manner.

A careful consideration of the foregoing description in conjunction with the invention as illustrated in the drawings will enable the reader to obtain a clear understanding and impression of the alleged features of merit and novelty sufficient to clarify the construction of the invention as hereinafter claimed.

Minor changes in shape, size, materials and rearrangement of parts may be resorted to in actual practice without departing from the invention as claimed.

Having described the invention, what is claimed as new is:

1. As a new article of manufacture, a honda for making up a toy lariat comprising an elongated substantially sector-shaped block, said block having broad top and bottom surfaces, having one longitudinal edge substantially straight from end to end and provided with a rope passage paralleling said edge and further provided with slot opening through said edge, the opposite longitudinal edge of said block being substantially straight from end to end and converging at one end toward the first-named longitudinal edge, one transverse end of said block being curvate and joining the corresponding ends of said longitudinal edges, said block being provided with a relatively short arcuate rope attaching and anchoring bore coplanar with said rope passage and said slot, one end of the bore opening through said curvate edge portion and being spaced away from and diverging in a direction from the corresponding ends of said slot and rope passage, and the other end of the bore opening through the intermediate portion of said second-named longitudinal edge, a length of rope having an end portion knotted against said second longitudinal edge and the adjacent portion threaded outwardly through a bore in a direction toward said curvate end and then bent and looped upon itself beyond said curvate end and fashioned into a noose, the latter embodying a portion fitted through said slot and lodged and friction retained in said passage, said portion being readily and safely releasable from said passage, by way of said slot when an abnormal pressure is exerted upon said noose.

2. A toy lariat comprising an elongated block having broad top and bottom surfaces, having one longitudinal edge substantially straight from end

to end and provided with a rope passage paralleling said edge and further provided with a slot opening through said edge, the opposite longitudinal edge of said block being substantially straight from end to end and converging at one end toward the first-named longitudinal edge, one transverse end of said block being curvate and joining the corresponding ends of said longitudinal edges, said block being provided with a relatively short arcuate rope attaching and anchoring bore coplanar with said rope passage and said slot, one end of the bore opening through said curvate edge portion and being spaced away from and diverging in a direction from the corresponding ends of said slot and rope passage, and the other end of the bore opening through the intermediate portion of said second-named longitudinal edge, a length of rope having an end portion knotted against said second longitudinal edge and the adjacent portion threaded outwardly through a bore in a direction toward said curvate end and then bent and looped upon itself beyond said curvate end and fashioned into a noose, the latter embodying a portion fitted through said slot and lodged and friction retained in said passage, said portion being readily and safely releasable from said passage, by way of said slot when an abnormal pressure is exerted upon said noose.
